US00D797162S

(12) **United States Design Patent** (10) **Patent No.:** **US D797,162 S**
Kunz (45) **Date of Patent:** **** Sep. 12, 2017**

(54) **LIP FOR GROUND ENGAGING MACHINE
IMPLEMENT AND/OR DIGITAL
REPRESENTATION THEREOF**

4,481,728 A 11/1984 Mulder et al.
4,570,365 A 2/1986 Bierwith
4,980,980 A 1/1991 Schadov et al.

FIG. 1 is a perspective view of a lip for ground engaging machine implement and/or digital representation thereof showing my design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines illustrate structure or features which form no part of the claimed design.

The dot-dash broken lines illustrate boundaries which form no part of the claimed design.

1 Claim, 5 Drawing Sheets
